UNITED STATES PATENT OFFICE.

GEORGE A. GEMMER, OF MARION, INDIANA.

VAPORIZER FOR EXPLOSIVE-ENGINES.

SPECIFICATION forming part of Letters Patent No. 726,671, dated April 28, 1903.

Application filed December 30, 1901. Serial No. 87,705. (No model.)

To all whom it may concern:

Be it known that I, GEORGE A. GEMMER, of Marion, county of Grant, and State of Indiana, have invented a certain new and useful Vaporizer for Gasolene-Engines; and I do hereby declare that the following is a full, clear, and exact description thereof, reference being had to the accompanying drawings, in which like numerals refer to like parts.

10 The object of this invention is to improve the construction and arrangement of the parts of a vaporizer for gasolene and other combustion engines. To that end there is provided improved means for mixing the air and the gasolene-vapor by using a series of screens, the gasolene and air passing through them at a right angle to each other, and also by providing two mixing-chambers—one a primary and the other a final mixing-chamber—20 with a valve for controlling the air-ports to said chambers, which increases the port to one chamber as it diminishes the port to the other chamber.

One novel feature consists of a gas-chamber intermediate said primary and final mixing-chambers, the outlet from which is controlled by the same valve that controls the outlet from the primary to the final mixing-chamber.

30 There are other novel features in this invention which, together with those above referred to, are explained in the accompanying drawings and the following description and claims.

35 In the drawings, Figure 1 is a side elevation of the vaporizer with a portion in vertical section and the cap at the left end and screens removed. Fig. 2 is a horizontal cross-section through the middle of Fig. 1. Fig. 3 is an elevation of the left end of Fig. 1, showing the device with the end cap and internal parts removed. Fig. 4 is an elevation of the cap at the left-hand end of the device. Fig. 5 is a plan view of the screen-mounting as shown in Fig. 6. Fig. 6 is a side elevation of the screens and their mounting. Fig. 7 is an end elevation of the valve that controls the air-ports to the mixing-chambers. Fig. 8 is a plan of said valve and its stem. Fig. 9 is 45 a horizontal section of a part of the device to show a modified construction of valve for

controlling the passage from the primary to the final mixing-chamber.

In detail the construction shown in the drawings to illustrate the general nature of this invention consists of a casing or shell 1, somewhat tubular in form and open at the two opposite ends thereof. At the end marked 2 the vaporizer is attached to the cylinder of the engine to be supplied with combustible fuel. At the opposite end the casing is closed by the removable cap 3. The air-inlet 4 is at the under side of the end adjacent to said cap 3, and an air-chamber 5 is formed separate from the other chambers by a partition 6. Said partition 6 has an air-port 7 through it, leading to the primary mixing-chamber 8, and also an air-port 9 through it, leading to the final mixing-chamber 10.

The passage of air from the chamber 5 to the chambers 8 and 10 is controlled by the valve 11, which is substantially semicircular and secured on one end of the stem 12, which is mounted centrally in the cap 3. The valve is pressed inward against the partition 6 by the spiral spring 13 and is controlled or actuated by the crank-like finger 14, which is secured on the outer end of the stem 12. The end cap 3 has a scale on it (shown in Fig. 4) to indicate the proper position of the finger 14 to enable the regulation of the valve 11. The end cap 3 has an inturned annular flange 15, which fits snugly in the casing and has catches 16 to engage pins 17 in the casing, whereby the cap is held in place and rendered readily removable.

The primary mixing-chamber 8 and the final mixing-chamber 10 are separated by a vertical and longitudinal partition 18, having an opening leading from one chamber to the other which is closed by the conical valve 19. Said valve is mounted on a stem 20, that is longitudinally reciprocable by the cam 40 on the shaft 41, driven by a suitable part of the engine in the casing at one end and in a sleeve 21 from the removable cap 22 at the other end. It is pressed into a closed position by the spring 23 and is actuated by a moving part of the engine. (Not shown.)

The inlet for gasolene is at the top of the vaporizer, (marked 24.) It is immediately over the outlet-opening 25, (shown in Fig. 2.)

through which the sediment is discharged. Therefore the gasoline drops from the opening 24 upon and through the series of sieves 26. These sieves are made of fine wire and 5 are located adjacent to the port 7 from the air-chamber 5 to the mixing-chamber 8, so that the air-current in passing from chamber 5 to chamber 8 goes through the sieves, and in that manner the gasoline is very thoroughly 10 vaporized.

The sieves 3 are secured at each end to posts 27 in the plate 28, that are secured in the side of the casing, as shown in Fig. 2, the set of sieves extending into the opening 29. (Shown 15 in Fig. 1.) A plurality of sieves is used to vaporize the gasoline effectually and mix the air therewith.

A gas-chamber 30, supplied through the inlet 31, is for natural gas or other gas when 20 the same is desired to be used with such an engine. This chamber 30 surrounds the conical valve 19, so that when the valve 19 is closed or in its seat it closes the chamber 30, shutting off all passage therefrom to either 25 the chamber 8 or the chamber 10. The one valve 19, therefore, controls this chamber as well as the gasoline-mixing chamber.

The modified form of valve shown in Fig. 9 is actuated in both directions by some 30 means (not shown) connected with the piece 32 of the valve-stem 20. The valve there shown is a hollow slide-valve having rings 33, 34, and 35, that close or open the passage-way to the chamber 10 from chamber 8. A casing 35 for said valve is formed by the partition 18, and the extension 36 forms the removable cap 22. The gas-chamber 30 is omitted, showing this modified form.

In operation the air enters the inlet 4 and 40 fills the chamber 5, and such portion of it as may be desired flows horizontally into the gasoline-mixing chamber 8 through the sieves 26. When valve 19 is actuated by some means pushing against the stem 20, the mixed gas 45 flows into the chamber 10 and from its outlet into the cylinder of the engine. Air enters directly into chamber 10 from chamber 5. The relative quantities of air entering chambers 8 and 10 is regulated by the valve 11, 50 which enables the passage-way into either one of said chambers to be wholly cut off. When one of the passage-ways is diminished, the other is correspondingly enlarged.

What is claimed as the invention, and which 55 is desired to be secured by Letters Patent, is—

1. In a vaporizer for combustion-engines, a number of screens for receiving the gasoline and through which the air passes, a removable block secured to the vaporizer, and posts extending inward from said block on which the screens are mounted parallel with each other.

2. In a vaporizer for combustion-engines, a 65 primary mixing-chamber with an air-inlet

thereto, a gasoline-inlet to said chamber, a final mixing-chamber with an air-inlet thereto, a valve-controlled passage-way from the primary mixing-chamber, and a single valve for controlling the air-inlets to said primary 70 and final mixing-chambers.

3. In a vaporizer for combustion-engines having a suitable casing, a primary mixing-chamber and a final mixing-chamber beside each other, a partition dividing said chambers with a valve-controlled passage-way 75 through it, another partition at a right angle to the former partition, air-ports leading to said primary and final mixing-chambers, and a single valve for controlling said air-ports. 80

4. In a vaporizer for combustion-engines, a primary mixing-chamber with an air-inlet thereto, a gasoline-inlet entering said chamber, a final mixing-chamber beside the primary mixing-chamber with a passage-way 85 leading from the primary mixing-chamber to the final mixing-chamber, an air-inlet to said final mixing-chamber, and a spring-pressed valve for controlling the air-inlets to both of said chambers. 90

5. In a vaporizer for combustion-engines, an air-chamber, a primary mixing-chamber and a final mixing-chamber, a partition between said mixing-chambers with a passage-way therethrough, a gasoline-inlet into the 95 primary mixing-chamber, a partition between the air-chamber and the mixing-chambers with an air-inlet through it to each mixing-chamber, and an adjustable valve for controlling the air-inlets into both mixing-chambers. 100

6. In a vaporizer for combustion-engines, the casing 1, the partition 18 forming two mixing-chambers, the partition 6 with an air-port entering each mixing-chamber, a cap for 105 closing the end of the casing, a valve 11 on the stem 12 mounted in said cap, the spring 13, and the finger 17 secured on the valve-stem, all arranged substantially as shown and described. 110

7. In a vaporizer for combustion-engines, a primary mixing-chamber, a final mixing-chamber, a gas-chamber between the two mixing-chambers, and a single valve for controlling the inlet into the final mixing-chamber 115 from the primary mixing-chamber and the gas-chamber.

8. In a vaporizer for combustion-engines, a casing provided with the partition 18 forming a primary and a final mixing-chamber, the 120 single valve 19 between said chambers, and the gas-chamber 30 surrounding said valve, all substantially as shown and described.

In witness whereof I have hereunto affixed my signature in the presence of the witnesses 125 herein named.

GEORGE A. GEMMER.
